(Cl. D30—1)

To all whom it may concern:

Be it known that I, Archie W. Roe, a citizen of the United States residing at Rock Island, in the county of Rock Island and State of Illinois, have invented a new, original, and ornamental Design for Cartridge Belt Links, of which the following is a specification, reference being had to the accompanying drawing, forming part thereof.

Fig. 1 is a perspective view of a cartridge belt link showing the new design;

Fig. 2 is a side elevational view thereof; and

Fig. 3 is a cross sectional view taken on the line 3—3 of Fig. 1.

The essential features reside in the specific configuration and appearance due to the serrated portion joining the single loop with the double loop in a manner as illustrated.

I claim:
